(57) **CLAIM**

The ornamental design for a hitch securing tool, as shown and described.

DESCRIPTION

FIG. 1 is a top front side perspective view of a hitch securing tool showing my new design;

FIG. 2 is a front view of the hitch securing tool;

FIG. 3 is a rear view of the hitch securing tool;

FIG. 4 is a left side view of the hitch securing tool;

FIG. 5 is a right side view of the hitch securing tool;

FIG. 6 is a top view of the hitch securing tool;

FIG. 7 is a bottom view of the hitch securing tool; and,

FIG. 8 is a top front side perspective view of the hitch securing tool in use.

The broken lines in FIG. 8 are illustrative of environmental structure forming no part of the claimed design.
